BLOW OUT COIL

John F. Tittle, Erie, Pa., assignor to General
Electric Company, a corporation of New York

Application March 10, 1933, Serial No. 660,269

4 Claims. (Cl. 200—147)

My invention relates to circuit-breaker blow-out coils and to a method of manufacturing the same, and has for an object the provision of a circuit breaker blowout coil of low cost and 5 symmetrical shape, lending itself to the construction of switches of improved space factor.

In the design of contactors of the air-break type, a blowout coil is connected in series circuit relation with the circuit breaker contacts so that 10 the full load current of the circuit breaker is utilized to produce a strong magnetic field to blow out the arc resulting from the opening of the circuit breaker. The continuous current rating of certain circuit breakers of this type, 15 such as used in railway locomotives, is quite high, on the order of 2500 amperes, so that a substantial amount of copper must be used in the blowout coil to prevent overheating. Similarly, a relatively large contact area must be provided 20 for the inner end of a spirally wound blowout coil to prevent overheating.

On a locomotive the permissible space for the control equipment is limited and it is therefore important to design the blowout coil of the contactor or circuit breaker so that the blowout coil is not the limiting feature in the width of the contactor and when a spirally wound blowout coil is used, to construct the coil so that 25 substantially the same conducting area is provided for the inner end of the coil as is provided in each of its turns.

In carrying out the present invention in one form thereof, I provide a spirally wound blowout coil which is not the limiting feature in the width of the circuit breaker. More specifically, 30 I provide a Y-shaped end on the conductor forming the blowout coil and spirally wind the conductor between the Y-shaped end to produce a blowout coil of symmetrical shape which occupies a minimum amount of space and yet provides the maximum current-carrying capacity. The two ends of the Y-shaped end are connected to carry jointly the load current flowing 35 through the main body of the conductor, these ends also forming supports for arc blowout plates.

For a more complete understanding of my invention reference should now be had to the drawing, Fig. 1 of which shows an elevation of 40 the arc chute and main current-carrying parts of a circuit breaker to which my invention has been applied; Fig. 2 shows a perspective view of the blowout coil construction in accordance with my invention; Fig. 3 shows the Y-shaped end 45 of the blowout coil of Fig. 2; while Figs. 4 and

5 show modifications of the Y-shaped end of the blowout coil.

Referring now to the drawing, I have shown my invention in one form as applied to a circuit breaker 10 having a fixed contact 11 and a 5 movable contact 12. The operating means for the movable contact 12, the supports, etc. are not shown as they form no part of my present invention. A blowout coil 13 of high conductivity material such as copper is connected in 10 series circuit relation with the contacts 11 and 12 of the circuit breaker so that the load current flowing through the blowout coil 13 produces a strong magnetic flux in the magnetizable 15 pole pieces or blowout plates 15 extending in spaced relation on opposite sides of the contacts 11 and 12 and connected by a magnetizable member 16 extending through the center of the blowout coil.

The blowout coil 13 is formed from a single 20 strip 18 of conducting material. The first step in constructing the blowout coil is to divide or split the end of the strip conductor 18 and to spread apart the divided ends 19 and 20 a distance greater than the width of the strip. The 25 conductor 18 is then spirally wound upon itself so that the spaced end portions 19 and 20 form leads to the inner turn 21 of the coil. It will be observed that the ends 19 and 20 provide substantially the same conducting area as the 30 conductor 18. By bringing out the leads from the inner end of the coil on opposite sides of the coil a well balanced design is obtained. The blowout coil is not a limiting feature in the 35 width of the circuit breaker.

As applied to the circuit breaker 10 of Fig. 1, the ends 19 and 20 of the blowout coil are secured to the contact tip supporting and conducting member 22 by soldering or brazing. Also supporting and fixing the blowout coil in 40 position are the screws 23 and 24 extending through the holes provided in the end 19 of the blowout coil and into the supporting member 22. Similarly, the end 20 of the blowout coil is secured by screws (not shown). The ends 19 and 20 are also used to support the magnetizable 45 pole pieces or blowout plates 15 and the core 16. One of the magnetizable pole pieces is held in position by means of the bolts 30 and 31 which pass through it and are screw-threaded 50 into the end 19 of the coil. Similar bolts (not shown) cooperate with the end 20 of the coil to support the other pole piece. The screw-threaded ends of the bolts are arranged to be 55 screwed into the ends 19 and 20 of the blowout

coil. Thus it will be seen that besides providing a compact construction of the blowout coil, the coil readily lends itself to the performance of other functions as, for example, the compact and stable method of supporting the pole pieces.

It will, of course, be understood that instead of dividing the end of the conductor 18 a Y-shaped end may be formed on the end of the conductor by welding or brazing a U-shaped conductor 33 having the same cross sectional area as the conductor 18 to the end of the conductor 18 as shown in Fig. 4. Or, an alternative is shown in Fig. 5 wherein separate conductors, 36 and 37 having the same cross sectional area as the conductor 18 are welded or brazed to the conductor 18 to form a Y-shaped end.

While I have shown a particular embodiment of my invention, it will be understood, of course, that I do not wish to be limited thereto since many modifications may be made, and I, therefore, contemplate by the appended claims to cover any such modifications as fall within the true spirit and scope of my invention.

What I claim as new and desire to secure by Letters Patent of the United States, is:

1. The combination with a circuit breaker of a blowout coil therefor, comprising a spirally wound strip conductor one end of which is divided longitudinally to provide leads on opposite sides of the turns of said coil to the inner end of said coil, a stationary contact for said circuit breaker, means supporting said leads of said conductor and said stationary contact, a pair of blowout plates for said circuit breaker, means for supporting said blowout plates from said divided leads of said conductor and on opposite sides of said stationary contact, and a magnetizable member extending through said coil and secured to said plates.

2. A blowout coil for circuit breakers comprising a strip conductor divided longitudinally to provide spaced end portions therefor, said conductor being spirally wound between said end portions to form a plurality of turns, said end portions being spread laterally in a plane parallel to the axis of said coil a distance sufficient to space the inner edge of said end portions

from said turns, blowout plates on opposite sides of said coil secured to said end portions, and a magnetizable core extending through the center of said coil and between said plates.

3. A blowout coil for circuit breakers comprising a strip conductor, one end being divided longitudinally to provide spaced end portions therefor, said conductor being spirally wound between said spaced end portions to form a coil having a plurality of turns, said end portions extending tangentially from the inner turn of said coil and being spaced laterally from said turns of said coil, the outer turn of said coil extending between said end portions and terminating in the opposite end of said conductor, said opposite end extending substantially at right angles to a plane taken through said end portions, blowout plates on opposite sides of said coil secured to said end portions, a magnetizable core extending through the center of said coil and between said plates, a stationary contact, a conductor, fastening means electrically connecting said conductor to said stationary contact and to said end portions, said conductor forming a support for said stationary contact.

4. A blowout coil for circuit breakers comprising a strip conductor formed of material having a conductivity substantially equal to that of copper, one end of said conductor being split longitudinally to provide spaced end portions therefor, said conductor being spirally wound between said end portions to form a plurality of turns, said end portions being spaced laterally from said turns of said coil and extending tangentially from the inner turn of said coil, a magnetizable core extending through the center of said coil, blowout plates on opposite sides of said coil secured to said end portions and to said core, a stationary contact located between said plates, a supporting conductor having one end secured to said end portions and its opposite end secured to said stationary contact, the outer turn of said coil extending between said end portions and terminating in spaced relation with said end portions.

JOHN F. TRITLE.
